Primary Examiner — Cathron Brooks*Assistant Examiner* — Teddy Falloway(74) Attorney, Agent, or Firm — Norton Rose Fulbright US LLP(57) CLAIM

The ornamental design for sealed frame, as shown and described.

DESCRIPTION

FIG. 1 is a front side view of an embodiment of a sealed frame where the sealed frame mount comprises three separate units; and,

FIG. 2 is a perspective view of the sealed frame of FIG. 1. The broken lines shown are included for the purpose of illustrating portions of the sealed frame that form no part of the claimed design.

1 Claim, 1 Drawing Sheet
